UNITED STATES PATENT OFFICE.

FREDRICK E. SCHNEIDER, OF HIGHLAND, WISCONSIN, ASSIGNOR OF ONE-HALF TO
ORREN ROSSING, OF HIGHLAND, WISCONSIN.

WIRE-STRETCHER.

1,273,676.

Specification of Letters Patent.

Patented July 23, 1918.

Application filed July 19, 1917. Serial No. 181,650.

To all whom it may concern:

Be it known that I, FREDRICK E. SCHNEIDER, a citizen of the United States, residing at Highland, in the county of Iowa and 5 State of Wisconsin, have invented certain new and useful Improvements in Wire-Stretchers; and I do hereby declare the following to be a full, clear, and exact description of the invention, such as will enable 10 others skilled in the art to which it appertains to make and use the same.

This invention relates to improvements in wire stretchers.

The object of this invention is to provide 15 a wire stretcher capable of being adjusted to a fencing wire so that an even pull may be distributed thereon prior to the stapling of the ends to posts.

A still further object of this invention is 20 to provide a wire stretcher, which will be simple, practical and comparatively inexpensive in construction and one that can be manufactured and sold at a low cost.

With these and other objects in view the 25 invention consists in the novel combination and arrangement of parts hereinafter more fully described and set forth in the claims hereto appended.

In the drawing

30 Figure 1 is a side elevation illustrating my improved wire stretcher as applied and in use,

Fig. 2 is a fragmentary side elevation illustrating the clamping plates and cam levers,

Fig. 3 is a sectional view taken on the line 3—3 of Fig. 2,

Fig. 4 is a sectional view taken on the line 4—4 of Fig. 2, and

40 Fig. 5 is a perspective view of one adjusting block and clamping plate and cam lever.

Like numerals of reference designate corresponding parts in all the figures of the drawing.

45 Referring to the drawing, the numeral 1 designates a substantially rectangular supporting member, provided with a spaced series of longitudinally extending slots 2. An adjusting block 3 is slidably arranged in

50 each of the slots 2 as illustrated. The blocks 3 are held against movement from its respective slot 2 in one direction by a rectangular strip 4. The strips 4 are secured to one face of each block intermediate the ends thereof as at 5, and these strips are arranged trans-

versely with relation to the supporting member 1 thus constituting a bearing as it has a sliding engagement with one face of the supporting member 1 and this permits the adjusting block 3 to move freely in its respective slot.

60 A clamping plate 5' is rigidly secured to the other face of each block adjacent the upper end thereof as at 6 and these plates are arranged transversely with relation to the supporting member and at right angles to the slots. The clamping plates 5' co-operate with the strips 4 and retain the blocks in the slots and also permit free sliding movement thereof. The under side 65 of each clamping plate is serrated or roughened as at 7 to constitute a gripping jaw.

A cam lever 8 is pivotally secured as at 9' to each adjusting block 3 and have their peripheral edges in close proximity to the 70 under roughened side of each of the clamping plates 5' to permit a fencing wire to be gripped tightly therebetween so as to permit the fencing wire to be evenly stretched when pull is applied to the supporting member 1.

75 Each of the cam levers 8 has a laterally extending reduced portion 9 formed integrally therewith which constitutes a handle and permits the cam levers to be rotated 80 so that the ends of a fencing wire may be readily placed between the peripheral faces of the cam levers and the under roughened side of each of the clamping plates 5'.

85 The supporting member 1 is provided on one longitudinal side and adjacent each end thereof with an eye 10 to which are secured the ends of the flexible chain 11 as at 12. The chain 11 has secured to its medial portion a connecting ring 13 to which is detachably secured the power applying or pulling mechanism, designated in its entirety by the numeral 14.

90 It can be readily seen that by the connection of the flexible chain to one longitudinal side edge of the supporting member 1, that when the fencing wire designated A in the drawing is arranged between the respective cam and clamping plates, an even pull will 95 be distributed to the wire, permitting the wire to be easily and quickly stretched and stapled to its respective post designated B in the drawing.

100 The pulling mechanism used in connection with this supporting member is illustrated 110

as being applied to an anchor post designated C having secured thereon adjacent its upper end a flexible connection 15 in which is secured the hook 16 carried by the sheave 17. An eye 18 is secured to the sheave 17 and has connected thereto one end of the cable 19. The cable 19 is passed through the sheave 20 which in turn is connected as at 21 to the connecting ring 13 of the wire stretcher as illustrated. The cable is then extended around the sheave 17 and has connected to its ends any suitable type of means for pulling the cable to permit the wire stretcher 1 to be pulled in the direction of the anchoring post C thus effectively stretching the fencing wires A secured to the supporting member through the medium of the cam levers 8 and clamping plate 5'.

In use, it can be readily understood that the adjusting blocks will position the clamping plates and levers in alignment with the ends of the fencing wires designated A. The ends of the fencing wires are arranged between the peripheral surface of each clamping lever 8 and its respective clamping plate 5'. The lever 8 is then moved by grasping the handle 9 and urging the same downwardly binding the fencing wires between the roughened underside of the clamping plate 5' and cam surface of the levers 8. In this way the fencing wires are firmly held to the supporting member 1 and the pulling mechanism is put in operation, thereby effectively stretching the fencing wires as will be obvious from the disclosure.

What is claimed is:—

1. A wire stretcher comprising a rec-

tangular supporting member provided with a series of spaced longitudinally extending slots, an adjusting block slidably arranged in each slot, a retaining strip secured to one face of each block and at right angles to the slot thereof, a clamping plate secured to the other face of each of the blocks and having its underside roughened, and a cam lever pivotally secured to each of the adjusting blocks in close proximity to the underside of the clamping plate.

2. A wire stretcher comprising a rectangular supporting member provided with a spaced series of longitudinally extending slots, an adjusting block arranged vertically in each slot, a strip secured transversely to one face of each block and having an abutting engagement with one face of the supporting member to retain the blocks in their respective slots and against movement in one direction, clamping plates secured to the other face of each block and preventing movement of the adjusting blocks in the other direction, a cam lever pivotally secured to one face of each block and located in close proximity to the under side of the clamping plates, said slots permitting of the vertical adjustment of the blocks to accommodate fencing wires, and a power applying mechanism adapted to be secured to the supporting member, as and for the purpose specified.

In testimony whereof I affix my signature in presence of two witnesses.

FREDRICK E. SCHNEIDER.
